CATCH ASSEMBLY

Earl Borchers, Rockford, Ill., assignor to American Cabinet Hardware Corporation, Rockford, Illinois, Rockford, Ill., a corporation of Illinois

Application May 8, 1940, Serial No. 333,885

6 Claims. (Cl. 292—1)

The invention relates generally to catches and more particularly to a catch assembly for a cabinet door.

The general object of the invention is to provide a novel catch assembly comprising a handle and operator adapted to be mounted on the outer face of a door, and a catch proper on the inner face of the door, in which the parts of the handle and operator are only loosely held in assembled relation before being placed on the door but are tightly held in such relation by the means for attaching the catch proper to the door, whereby the entire assembly may be readily mounted on the door.

It is also an object to provide a catch assembly of the foregoing character, which is of simple construction and which may be inexpensively manufactured because of the simplicity of the assembly of the various parts, both of the handle and operator and of the catch proper.

Other objects and advantages will become apparent from the following description taken in connection with the accompanying drawing, in which:

Figure 1 is a side elevational view taken edge-wise of the door of a catch assembly embodying the features of the invention.

Fig. 2 is a horizontal sectional view taken on the line 2—2 of Fig. 1.

Fig. 3 is a vertical sectional view taken on the line 3—3 of Fig. 2.

Fig. 4 is a horizontal sectional view taken on the line 4—4 of Fig. 3.

Fig. 5 is a perspective view showing a portion of the handle structure.

Fig. 6 is an enlarged fragmentary perspective view of the catch proper.

The catch assembly herein disclosed is of the type particularly adapted for use with either wood or sheet metal cabinets. It comprises a catch proper adapted to be mounted on the inner face of the door to engage the frame in order to hold the door closed, and a handle and operator portion adapted to be mounted on the exterior face of the door. The handle and operator portion is usually so constructed as to permit a person to release the catch and then pull the door open. In many catches of this general character, a simple push pin is utilized to provide the operating connection between the handle and operator on the exterior face of the door and the catch on the inner face of the door. The present device is of this type.

In most catch assemblies of this type, the handle and operator portion is usually completely

assembled, and the parts thereof are rigidly held together before this portion is mounted on the door. More particularly, the handle and operator portion usually comprises a handle having a base portion rigidly secured thereto, the base portion serving as a means by which the handle is attached to the door. However, the rigid assembly of the handle and its base usually involves certain assembly operations which add to the cost of the device. Since catch assemblies of this character are sold at a relatively low price, the cost of assembling the handle and the base is a material part of the total cost.

By the present invention, the assembly cost of the handle and operator portion is reduced by merely loosely retaining the base of the handle within the handle, and the two are rigidly secured together by the means by which the device as a whole is secured to the door. Loosely retaining the base within the handle requires the simplest of assembly operations, and also permits of a slight adjustment of the parts as they are being mounted on the door.

The catch proper also includes as a feature a novel construction whereby the back plate of the catch is secured to the body thereof by means extending through the apertures for the mounting screws, thus eliminating the necessity for providing separate apertures for such means.

As shown in the drawing, the door is indicated at 10, the catch proper at 11 and the handle and operator portion is indicated generally at 12. In the present instance, the catch proper comprises a body 13 in which is mounted a shiftable bolt 14 adapted to engage the frame of the door or a strike mounted thereon. The catch proper is preferably provided with a pair of ears 15 extending laterally from the body 13 and provided with apertures 17 to receive mounting screws 16. The bolt 14 and other parts of the catch are held within the body 13 by means of a back plate 18.

In order to provide a simple construction to retain the back plate 18 in place on the body 13, the plate is provided with means extending through the aperture 17 securing the back plate to the ears 15. In the present instance, such means comprises a plurality of tangs 19 formed from the metal punched from the apertures in the back plate and then bent to extend through the apertures 17 and slightly over the front face of the ears 15. Thus, the back plate is rigidly held in place and no extra apertures are required for said means.

The handle in the present instance comprises a sheet metal structure drawn and bent to pro-

vide a pair of spaced, relatively flat walls 20, with the outer or bent edge of the handle, indicated at 21, shaped to present a decorative appearance. In the preferred form, the handle has a downwardly extending portion 22 spaced from the door so that it may be grasped by the hand in order to pull the door open.

Within the handle is mounted an operator 23 which is pivotally supported between the spaced walls 20 by a fixed pin 24. At its upper or inner end, the operator 23 is provided with a curved portion 25 adapted to bear against the head of a pin 26 extending through the door and into the catch 11. Movement of the pin 26 inwardly of the door by the pivotal motion of the operator 23 causes the bolt 14 of the catch to be shifted to its release position, a spring (not shown) in the catch serving to return the pin 26 and the operator 23 to their normal positions. The lower end of the operator 23, which is here indicated at 27, is shaped to lie partially within the portion 22 of the handle, as shown in Figs. 1 and 3, and is in spaced relation to the door. Thus by inserting the fingers between the lower end 27 of the operator and the door and pulling, such pull first causes the operator to swing about its pivot and release the catch bolt 14, and then swings the door open.

In order to secure the handle to the door, each side wall 20 thereof is provided with an inwardly extending flange 30 bent toward each other and extending longitudinally of the handle. Within the handle is placed a base 31 comprising an elongated strip of metal inserted into the handle through the open lower end thereof and held against upward movement by the bent portion 21 of the handle. In order to loosely secure the base within the handle, a tongue 32 is punched in the handle in the same operation in which the base as a whole is formed. After the base has been inserted into the handle, the tongue 32 is bent at a right angle to engage the pivot pin 24, as shown in Figs. 3 and 4, and thus loosely retains the base within the handle. The base is preferably provided with a flanged aperture 33 to serve as a guide for the push pin 26.

In order to secure the base 31 to the door, a pair of internally threaded tubular members or nuts 35 are secured in apertures in the base as by riveting. These nuts 35 are so located as to receive the ends of the screws 16 by which the catch is secured to the door. When the screws 15 are tightened, the base is rigidly attached to the door, and since the flanges 30 on the handle lie between the base and the door, the handle is thereby rigidly held in place. Thus, while the base 31 is only loosely retained within the handle before being mounted upon the door, it rigidly holds the handle in place as an incident to being secured to the door.

From the foregoing, it will be apparent that the catch assembly herein shown is of a very simple construction and may be inexpensively manufactured, particularly because of the simplicity of the assembly of the various parts. The manufacturing cost is reduced because the handle and its base do not have to be rigidly secured to each other before mounting on the door, but the two are rigidly secured together when the parts of the device are secured to the door. However, this does not increase the cost or time required to mount the device on the door since the operations required in so mounting the device are no more than would be required if the handle and

its base were rigidly connected. Moreover, the assembly of the catch proper is simplified since the back plate 18 is rigidly held in place by means extending through the apertures in the catch body for the mounting screws.

I claim as my invention:

1. A catch assembly for a door comprising, in combination, a hollow handle and operator portion adapted to be mounted on one side of a door, 10 a catch portion for the other side of the door, and a push pin connecting said portions for operating the latter, said handle and operator portion including a base loosely retained within the handle before mounting on the door, and means for securing both the catch portion and said base tightly to the door and clamping a part of said handle between said base and the door.
2. A catch assembly for a door comprising, in combination, a handle and operator portion 20 adapted to be mounted on one side of a door, a catch portion for the other side of the door, and a push pin connecting said portions for operating the latter, said handle and operator portion comprising a handle having a pair of longitudinally extending flanges on its rear face, an operator pivotally mounted in the handle, and a base inserted in said handle under said flanges and loosely retained therein against endwise movement, and a pair of screws for securing said 30 catch portion to the door and threaded into the base and thereby rigidly clamping said flanges between the base and the door.
3. A catch assembly for a door comprising, in combination, a handle and operator portion 35 adapted to be mounted on one side of a door, a catch portion for the other side of the door, and a push pin connecting said portions for operating the latter, the handle of said handle and operator portion comprising a pair of spaced side walls having a pair of longitudinally extending flanges bent toward each other, a base located inside of said handle along the inner face of said flanges, and means extending through the door for rigidly securing the catch portion and said 45 base to the door and thereby clamping said flanges against the door.
4. A catch assembly for a door comprising, in combination, a handle adapted to be mounted on one side of a door, a catch adapted to be mounted on the other side of the door, said handle being hollow, an operator pivotally supported within the handle by a cross pin, a base for said handle comprising a strip of metal inserted lengthwise into the handle, said base having a tongue struck therefrom to engage said cross pin and loosely retain said base longitudinally within said handle, and securing means for the catch extending through the door and rigidly securing said base in place with the handle clamped to the door.
5. For use in a catch assembly for a closure wherein a catch is mounted on the inner face thereof, a handle assembly comprising a hollow body portion having a pair of spaced side walls and a pair of longitudinally extending flanges bent toward each other and being adapted to lie in contact with the outer face of a closure, a base for said handle loosely but permanently retained inside of said handle along the inner face of said flanges before being secured to the closure thus permitting adjustment of the handle relative to the base during mounting thereof on the closure, said base being adapted to be rigidly secured to the outer face of the closure by means used in securing the catch and thereby

engage said flanges and rigidly clamp the handle in place, and passages through said base and between said flanges for receiving said catch and handle securing means.

6. A catch assembly for a door comprising, in combination, a handle and operator portion adapted to be mounted on one side of a door, a catch portion for the other side of the door, and a push pin connecting said portions for operating the latter, the handle of said handle and operator portion comprising a pair of spaced side walls having a pair of longitudinally extending

flanges bent toward each other, a base loosely fitting within said handle along the inner face of said flanges, and means extending through the door for rigidly securing the catch portion and said base to the door and thereby clamping said flanges against the door, the loose fitting of the base within the handle permitting relative adjustment therebetween during the clamping operation so that the handle may be adjusted to a limited extent relative to the other parts of the assembly.

EARL BORCHERS.
